UNITED STATES PATENT OFFICE

HARRY H. WEINTRAUB, OF WILKES-BARRE, PENNSYLVANIA, ASSIGNOR OF ONE-HALF TO MAX DATTNER, OF WILKES-BARRE, PENNSYLVANIA

DESIGN FOR A SET OF PLAYING CARDS

Application filed August 27, 1931. Serial No. 40,935. Term of patent 14 years.

To all whom it may concern:

Be it known that I, HARRY H. WEINTRAUB, a citizen of the United States, residing at 476 S. Franklin Street, Wilkes-Barre, in the county of Luzerne and State of Pennsylvania, have invented a new, original, and ornamental Design for a Set of Playing Cards, of which the following is a specification, reference being had to the accompanying drawing, forming a part thereof.

In the drawing:

The figures are face views from a set of playing cards illustrating my new design. The same scheme of ornamentation is carried throughout the entire set of cards.

I claim:

The ornamental design for a set of playing cards, as shown and described.

HARRY H. WEINTRAUB.
